FORCED DRAFT BUFFER

Morris Schloss, Bronx, N. Y.

Application September 26, 1947, Serial No. 776,302

5 Claims. (Cl. 51—193)

1

The present invention pertains to improvements in forced draft buffers and methods of making the same.

An object of the invention is to provide improved rotary buffering means made of fabric in which the structure is such as to permit the passage of ventilating air throughout the entire body of the buffer.

A further object is to provide an improved buffer ring or section made of a plurality of single layers of fabric and so constructed that ventilating air has access to the inner circumference of all individual layers, the buffer sections being adapted to be built up in multiple to give any desired width of rotary buffer.

Another object is to provide an improved buffer section not subject to undue spreading under pressure.

A further object is to provide a suitable method for forming the improved buffer sections of bias cut material whereby the principal threads of all individual fabric layers throughout the section are inclined in the same direction with respect to the direction of rotation.

Another object is to provide improved means of mounting and retaining the buffer sections in multiple.

Another object is to provide hollow cylindrical mounting means of the above nature constructed so as to permit the free access of the ventilating air to the inner edges of all individual fabric layers in the buffer.

Another object is to provide mounting means of the type mentioned including means to force air from the interior of said hollow cylindrical means directly outward throughout the fabric layers of the buffer.

Other objects and advantages of the invention will appear during the course of the following description in connection with the accompanying drawings in which:

Figure 1 is a longitudinal section of a typical preferred form of buffer assembly;

Figure 2 is a cross sectional view approximately in the plane 2—2, Figure 1, taken before application of the gripper rings;

Figure 3 is an outer end elevation of an alternative assembly showing a means of regulating the passage of air into the interior;

Figure 3a is a detail sectional view of the shutter or regulating means;

Figure 4 is an elevation of a preferred form of gripper ring;

Figure 5 is an enlarged fragmental detail view of one of the gripping points taken in the plane 5—5, Figure 4;

2

Figure 6 is an enlarged sectional view of a portion of the hollow mounting drum or hub showing the lock joint forming a key;

Figure 7 is a fragmental detail section of an alternative form of the drum;

Figure 8 is a diagrammatic side elevation illustrating the first step in the method of forming the improved buffer section;

Figure 9 is a diagrammatic bottom view of the same;

Figure 10 illustrates an optional second step in carrying out the method;

Figures 11—17 inclusive, illustrate successive steps by which the method is carried to completion;

Figure 18 is an enlarged fragmental view of the inner edge of the completed section;

Figure 19 is an edge elevation of the completed section;

Figure 20 is a side elevation of the same viewed in the direction 20—20, Figure 19; and

Figure 21 is a similar view taken in the direction 21—21, Figure 19.

Referring to Figures 1 and 2, the numeral 25 denotes a buffer spindle upon which is mounted a circular rear member 26 having a forwardly directed cylindrical shoulder 27. A hollow cylindrical drum 28 is fitted at one end on the shoulder 27. A front member 29, also having a cylindrical shoulder 30, supports the outer end of the drum 28. The member 29 which is retained on the spindle 25 in any suitable manner, preferably by a nut 31, is provided with spokes 32 and is adapted to admit air into the interior of the drum 28. When in driving position, the members 26 and 29 may be further secured to the spindle 25 by set-screws 61 or the like.

The drum 28 may conveniently be formed of sheet metal bent into cylindrical form and having a lock joint 33 which performs the double function of holding the drum in shape and also acting as a driving key.

Thin gripper rings 35, having a plurality of sharp points 36 preferably turned at right angles to the face of the rings 35 by stamping or the like, are mounted on the drum 28 so that the points 36 grip the sides of the buffer sections 34, one ring 35 being provided on each side of each section.

Key notches 37 in the inner circumference of rings 35 are adapted to engage the lock joint 33 of the drum 28 in driving relation. Since the inner circumferences of the buffer sections 34 are resilient as hereinafter set forth, no key notches are necessary in the fabric members to

permit their installation over the shallow lock joint 33.

The hub or drum 28 is provided with a large number of forwardly directed louvres 38 which place the inner edges of the buffer section 34 in direct communication with the interior of the drum. The inner inclined walls or blades 38a of the louvres 38 are adapted to force air outward, the drum thus comprising a centrifugal fan or blower.

The operation of the device as a whole will be set forth after description of the individual buffing sections and method of forming the same.

Referring to Figure 8 and the successive method figures, as previously noted, the buffer section in preferred form may be constructed as follows:

A strip of suitable buffing fabric 39 is cut on the bias so that the principal or grain threads 40 in the weave thereof are inclined in one direction throughout the strip. In the case of sewed joints in the strip, the joined pieces are so brought together as to preserve the same inclination of the principal threads as noted. The strip 39 is then wound spirally into a cylinder 41 on a mandrel 42 as illustrated in Figures 8 and 9.

In winding the cylinder 41, the tension on the strip 39 is progressively increased, by which means the successive layers of the cylinder 41 are more heavily stressed from the inside to the outside of the cylinder, for a purpose hereinafter set forth.

When the desired number of layers have been built up on the mandrel 42, a small sticker 43 or other suitable temporary retainer is applied to the final end 44 of the wrap and the cylinder 41, after being slid wholly or partly off the end of the mandrel 42, may be loosely basted through all layers at 45 near one end of the cylinder.

As the next step, a plurality of equally spaced holes 46 are punched radially through the cylinder near the end thereof as shown in Figure 11.

A cord 47, Figure 12, is then laced in and out through the holes 46.

The cylinder 41 is next placed on a jig 48 of any suitable form as illustrated in Figure 13, in which the upper portion of the jig 48 includes a second cylindrical mandrel 49 of a size corresponding to the desired inner diameter of the completed buffer section.

The ends 50, 51 of the cord 47 are then pulled across each other tightening the cord 47 and drawing the ends of the cylinder 41 bodily inward in a series of uniform convolutions 52 as shown in Figure 14.

When the cord 47 has been tightened to the desired degree wherein the inner edges of the convolutions 52 embrace the cylindrical mandrel 49, the cylinder 41 has been reformed into an annular flat shape as shown in Figure 16, and as the latter shape is substantially the final form of the buffing section, it will hereinafter be referred to by the section's originally assigned number 34.

At this point the cord 47 is tied in a knot 47a as illustrated in Figure 15, and the ends 50, 51 are clipped off. As a final operation the section 34 may be flattened hydraulically or by other pressure means between guided upper and lower pressure members 53, 54, Figure 17.

As a result of the above processes, the interior section 34 comprises a series of uniform convolutions 52 in the cylindrical surface formed by the inner raw edges of the fabric material as shown in enlarged detail in Figure 12.

Due to the fact that the edges of the fabric

layers are not individually gathered, but the assembly of layers is bent into a series of comparatively large convolutions in which the individual layers are mutually supporting, the inner zone of the section is inherently firm and requires no binding rings or means other than the single cord 47 to hold it in shape during storage, handling and installation on the buffering lathe.

The original diameter of the cylinder 41 and the fabric strip 39 are so proportioned to the desired final dimensions of the finished section, that the convolutions 52, though tightly pressed together in their inner zone, taper outward to shallow waves or transverse depressions 55 at the outer periphery of the section 34 as shown in Figure 19. By this means, the finished section, after having been pressed as previously described, comprises an annular ring of uniform thickness with sufficient density throughout its extent to provide ample resistance to pressure applied to its periphery during a buffering operation without spreading of the individual fabric layers apart. At the same time, since the inner circumference of the section is formed of many uniform convolutions 52 held in proper relation by the drawstring 47, the structure provides many small interstices or openings such as 56 among and between the individual layers of fabric rather than at the sides of the entire section, which latter in practice are flatly embraced by the gripper rings 35, the internal pores or openings 56 leading outward from the inner edges of the section to the periphery thereof throughout the entire thickness of the section.

It has been previously noted that in winding the cylinder 41 from which the section 34 is formed, the tension on the strip 39 was progressively increased. As a result of this increasing pressure, the outer layers were stretched progressively more than the inner layer so that when the cylinder is formed into a flat ring as described, the additional contraction of the outer layers compensates for the slight increase in circumference of the successive wraps as the cylinder was built up. By this means the final conformation of the layers in the section 34 is rendered uniform throughout. Since the section 42 is formed as described by drawing in one end of the cylinder 41, the radial extent of all individual layers of the finished section 34 is the same. This eliminates or minimizes the necessity for final peripheral trimming of the section in order to secure a uniform cylindrical outer surface, an obvious advantage and saving of material over former methods in which a section has been formed by gathering or crimping a cylinder inward around its middle zone. In the case of a section formed by the latter method, the initial profile of the outer circumference is necessarily convex, requiring considerable trimming and waste of material to render it cylindrical.

A further advantage achieved by the method of drawing in one end of the cylinder is that in all layers of the finished section, the principal threads or warp of the fabric layers are inclined in one direction from the radial direction, as illustrated in Figures 20, 21, which figures represent views of opposite ends of the same section 34, Figure 19.

In operation in the direction indicated by the arrows in Figures 20, 21, it will be seen that the principal threads 40 slope backward with respect to the direction of rotation and with respect to any object such as 57 thrust against the section 34 for buffering. Similarly, if the buffer is revolved in the other direction, all principal

threads are inclined forward against the work in the direction of rotation. It has been determined by experience that when the warp or principal threads are uniformly inclined as noted, the uniformity of work and the quality of work are much superior to those of buffers in which all or part of the principal threads are sloped at various angles with respect to the direction of rotation. This is due to the fact that forwardly inclined threads produce a different type of effect on the work than those inclined rearwardly. Thus a section made as described herein may be used for either desired type of work, for example roughing or polishing, simply by arranging it to revolve with the principal threads inclined in the chosen direction, and with uniformly high quality of either type of work.

The above described quality of uniformly sloping principal threads throughout the section is one of the principal advantages of the described present method of forming sections, as it will be obvious that in sections made by the former method of crimping a fabric cylinder inward in its middle zone, the principal threads of half the finished section will be sloped rearwardly and the other half forward, resulting in uneven wear and irregular or inferior buffing. Furthermore, the buffer section formed by the present method as described, without middle crimping of the fabric cylinder, eliminates the tendency for individual sections to spread apart in the middle under buffing pressure.

The general operation of the device is as follows:

The desired number of buffer sections 34 is stacked on the drum 28 with gripper rings 35 between their inner rims as shown in Figure 1.

A pressure ring 58 is then placed on the outer end of the drum 28 and the member 29 is drawn tightly inward to clamp the assembly together by means of the nut 31 and the setscrews 61 are tightened. As the buffering assembly is revolved at high speed to perform its function, louvre blades 38a force a blast of air from the interior of the drum 28 directly out through the openings 38 and through the previously described interstices 56 throughout the entire extent of the buffering assembly. By this means air is forced under pressure among and between all individual fabric layers of the buffering assembly, the outward passage of air not being limited to zones between sections as in the case of buffers in which the sections are internally bound by metal or other imperforate rings, or where the sections are mounted on solid guiding surfaces. Absence of intermediate supporting discs or the like in the interior of the drum 28 permits unobstructed passage of air to the louvres 38 and thence to the exposed inner edges of the fabric layers. The sirocco fan effect of the louvre blades 38a gives comparatively high direct air pressure which assures circulation through the smallest passages, thus allowing the use of a buffer of high density and firmness, as previously noted, while maintaining ample ventilation throughout the buffer.

For some types of buffering it may be desired to modulate the powerful pressure effect of the sirocco or centrifugal fan drums. For this purpose means may be provided to throttle the intake of air to the interior of the assembly, as illustrated in Figures 3 and 3a, in which a pair of apertured plates 62 and 63 are clamped on the spindle 25 between the member 29 and the nut 31. The plates 62 and 63 may be rotarily adjusted with respect to each other as a shutter to

provide a variable common orifice 63a giving any desired throttling effect on the incoming air.

If desired, the fan drum may be constructed in alternative form as illustrated in Figure 7 in which a large number of small tabs 59 are struck inward at an angle with the main drum cylinder 28a so as to underlie perforations 60. When such a drum is revolved in the direction indicated by the arrow, Figure 7, the tabs 59 scoop the air outward through the perforations 60, also after the manner of a sirocco fan as previously set forth.

In practice, various lengths of drums 28 may be provided to allow the building up of buffer assemblies of any desired length. As all the blades of the fan drum are on the inside of the drum, they are not a source of danger to the operator as in the case of exterior fans.

While the invention has been described in preferred form, it is not limited to the exact embodiments illustrated, as various modifications and changes may be made without departing from the scope of the appended claims.

What is claimed is:

1. In a device of the character described, in combination, a rotary spindle, a hollow drum of greater diameter than said spindle, means to support said drum concentrically on said spindle whereby a chamber is formed within said drum about said spindle, said drum having louvres forming openings through the periphery thereof to said chamber, an annular buffer comprising a plurality of fabric layers supported on said drum and having interstices between individual layers forming radial passages throughout said buffer, the inner edges of said individual fabric layers being in engagement with said drum whereby said interstices are disposed in communication with said louvres, said louvres having inclined blades adapted to force air from said chamber out under pressure through said louvres and said radial passages.

2. That method of forming a rotary buffer section which includes the steps of winding an unfolded strip of bias-cut fabric spirally in successive layers to form a hollow fabric cylinder, punching a ring of equally spaced holes radially through said cylinder in a zone adjacent one end thereof, lacing a cord alternately inward and outward through successively adjacent holes throughout said ring, retracting the protruding ends of said cord to draw said end of said cylinder inward in a series of uniform convolutions whereby said cylinder is converted into a substantially flat annulus of predetermined inner diameter, and securing the ends of said cord.

3. A method as described in claim 2 in which the winding tension of said strip is progressively increased as said cylinder is built up in said successive layers.

4. A method as claimed in claim 2, including the step of axially compressing said substantially flat annular section while radially supporting said section throughout the inner circumference thereof.

5. A device as claimed in claim 1 wherein said drum is formed of sheet metal bent in cylindrical form and joined in an outwardly extending lapped seam, wherein said buffer is built up of a plurality of sections each comprising a plurality of said individual fabric layers, and including means between said sections to grip the inner zones of said sections, said gripping means having

key notches therein engaging said outwardly extending seam.
